ENGINE STARTING APPARATUS

Roland Chilton, Keyport, N. J., assignor, by
mesne assignments, to Eclipse Machine Com-
pany, Elmira Heights, N. Y., a corporation of
New York

Application January 30, 1929, Serial No. 336,308

1 Claim. (Cl. 192—12)

This invention relates to engine starting mechanism, and more particularly to manually operable means for cranking internal combustion engines.

5 It is an object of this invention to provide a starter mechanism of the above character which is small and light for powerful and efficient in operation.

Another object is to provide an engine starter 10 in which the mechanism and the operator are protected from injury due to backfire of the engine and which serves to frictionally arrest reverse rotation of the engine crankshaft.

Other objects and advantages will be apparent 15 to those skilled in this art from the following description taken in connection with the accompanying drawing in which—

Fig. 1 is a longitudinal mid-sectional view of the device;

20 Fig. 2 is a detail perspective view of the clutch shifting sleeve; and

Fig. 3 is a perspective detail view of a ratchet sleeve and its actuating spring.

Referring first to Fig. 1 of the drawing, 10 25 indicates a casing member having a radial flange 11 provided with a series of equally spaced openings 12 therein through which bolts 13 are adapted to pass and clamp the starter casing against the crankcase or other suitable portion 30 14 of an engine to be started in radially adjustable position. The casing 10 is open at one side, and a suitable closure member 15 is formed to fit closely over said opening and is suitably attached to said casing as by means of cap 35 screws 16.

Casing 10 is provided with an offset portion 17 providing a bearing seat 19. A driving barrel member 20 is rotatably mounted within the extension 17 of casing 10, and projects outwardly 40 through the opening of portion 17 and has a suitable universal connection with a cranking shaft 21 as by means of the slotted spherical head 22 on said shaft, and the pin 23 fixed transversely within the barrel and traversing the 45 spherical head 22.

The outer portion of the barrel 20 is externally splined as indicated at 24, and a sleeve 25 (Fig. 3) provided with ratchet teeth 26 is splined upon said barrel to move freely longitudinally there-

50 of. A ring member 27 having opposing ratchet teeth 28 is seated against the outer end of the extension 17, and is suitably fixed thereto as by means of cap screws 29. A cap member 30 is adapted to seat against the ring 27, surrounding 55 the ratchet teeth 28 and the ratchet member 25,

and extending inwardly to form an outer bearing for the barrel member 20, and a spring member 31 is adapted to seat against the inwardly extending portion of the cap 30 and bear against a shoulder on the ratchet sleeve 25 60 in order to yieldingly maintain the ratchet teeth in engagement with each other, said teeth being shown separated in Fig. 1 for clearness of illustration.

A pinion shaft 32 is rotatably mounted within 65 the extension 17, having a suitable bearing such as the bushing 33 within the barrel member 20 at one end, and being provided near the other end with a suitable antifriction bearing 34 mounted in the bearing seat 19. Friction clutch 70 disks 35 and 36 are splined respectively to the concentric portions of the pinion shaft 32 and the barrel 20, and are maintained in preset driving engagement by suitable means such as the spring washers 37 which seat against an in-turned portion 38 of the driving barrel 20, and an adjusting ring 39 threaded within the inner 75 end of said barrel.

A distance piece or sleeve 40 is preferably inserted within the extension 17 to maintain the bearing 34 on its seat, and registering openings 41 and 42 may be formed in said sleeve and extension respectively in order to give access to the nut 39 whereby the same may be adjusted, suitable closure means such as indicated at 43 being provided to exclude dirt and foreign substances from the parts within the casing.

80 Casing 10 is provided centrally thereof with a bearing sleeve 44 arranged substantially perpendicularly to the extension 17, and a sleeve 45 having a radial flange 46 is freely journaled therein. A bevel gear member 47 is mounted on the flange 46, being integrally formed therewith or suitably attached thereto as by means of rivets 48, and is provided with teeth 49 adapted to mesh with the teeth 50 on the pinion shaft 32, whereby 85 rotation of the pinion shaft will be transmitted to the sleeve 45. A connecting element in the form of a clutch member 51 is splined within the sleeve 45 as indicated at 52, and extends outwardly from the casing 10 where it is provided with 90 clutch jaws 53 adapted for unidirectional engagement with the crankshaft or other member of the engine to be started.

95 A split elastic sleeve 54 (Fig. 2) is mounted upon a smooth portion of the clutch member 51, in frictional engagement therewith, and has an inclined slot 55 formed therein. A cylindrical 100 stud 56 is mounted radially in an outer portion of the sleeve bearing 44, being fixed therein in 105 110

any suitable manner as by means of a transverse pin 57, and has an inwardly extending flattened portion 58 adapted to extend within the inclined slot 55 of the spring sleeve 54. The inclination 5 of the slot is such that rotation of the sleeve 54 with the clutch member 51 in a counterclockwise direction, as viewed from the right in Fig. 1, will cause the sleeve 54 to be projected outwardly to the left and thus move the clutch member 51 into 10 engagement with the engine member to be started. The clutch member 51 is provided with a central bore 59, and a stud 60 is suitably fixed at the inner end thereof as by means of a set collar 61. The stud 60 extends through a central bearing 62 in the closure member 15, and a spring 63 is mounted upon the projecting portion thereof, being confined thereon by suitable means such as the adjusting nut 64 so as to maintain the driving clutch member 51 normally in its retract- 15 ed position.

In order to relieve the flange 46 and the bearing 44 from twisting strain caused by the reaction of the gears 47 and 50, and in order that proper meshing of said gears may be maintained 20 under all conditions, an antifriction roller 65 is mounted to bear against the back of the gear member 47 opposite to the pinion 50. The roller 65 is adjustably mounted in any suitable manner as by means of a stud 66 threaded obliquely in 25 the casing 10 and held in adjusted position as by means of the lock nut 67.

In operation, rotation of the pinion shaft 32 in a counterclockwise direction, as viewed from below in Fig. 1, will cause counterclockwise rotation of the gear member 47 and the clutch member 51. The initial rotation of the clutch member 51 causes the sleeve 54 to slide outwardly on the stud 56, causing the clutch member 51 to be projected into engagement with the engine shaft 25 whereby further rotation of the clutch member is transmitted thereto. When the engine starts and overruns the clutch jaws 53, the clutch member 51 is returned to its retracted position due to the inclination of said clutch jaws and aided 40 by the retracting spring 63.

If the engine should backfire for any reason while the clutch jaws 53 are in engagement with the engine shaft, the clutch member 51 will be rotated in a reverse direction, and will reversely 50 rotate the gear 47 and pinion 50. The barrel member 20, however, is prevented from reverse rotation by the engagement of the ratchet sleeve

25 with the fixed ratchet teeth 28, so that the clutch disks 35 and 36 are caused to slip on each other thus quickly stopping the reverse rotation of the engine, while protecting the cranking mechanism and the operator from injury there- 80 by.

It will be noted that the radial arrangement 85 of the pinion shaft 32 permits the starter mechanism to occupy very little space, particularly in a longitudinal direction, and further, allows a wide variation in the angular position assumed by the cranking shaft 21, thus rendering the starter adaptable to different situations and relationships with respect to the fuselage and the engine mounting. 90

Although but one embodiment of the invention has been shown and described in detail, it is to be expressly understood that the illustrated embodiment is not exclusive, and various other 95 embodiments will now present themselves to those skilled in the art, while changes may be made in the construction, arrangement and proportions of parts, and certain features used without other features, without departing from the spirit of the invention. Reference is therefore to be had to 100 the claim hereto appended for a definition of the limits of the invention.

What is claimed is:

In a device of the class described, a member 105 to be driven, a centrally and transversely apertured support having a series of ratchet teeth disposed about the centrally apertured portion thereof, a sleeve rotatable within said support, said sleeve terminating in a flange provided with ratchet teeth corresponding to those on said support, means engaging said flange and tending to hold said sleeve teeth in mesh with those of said support, but yieldable to enable said sleeve to rotate in one direction only, a driving sleeve 110 splined within said first named sleeve, a friction connection between said driving sleeve and driven member whereby the latter may rotate in a reverse direction while the ratchet teeth prevent such reverse rotation of the driving sleeve, and a nut threadedly engaging said driving sleeve 115 to fix the torque transmitting capacity of said friction connection, said nut being adjustable through the transversely apertured portion of said support after assembly of all the parts above recited. 120
